CLAIM

I claim the ornamental design for a wireless receiver, as shown and described.

DESCRIPTION

FIG. 1 is a perspective view of a wireless receiver of the present invention;

FIG. 2 is a front view thereof;

FIG. 3 is rear view thereof;

FIG. 4 is a first side view thereof;

FIG. 5 is a second side view thereof;

FIG. 6 is a top view thereof; and,

FIG. 7 is a bottom view thereof.

The broken lines shown represent unclaimed subject matter and form no part of the claimed design.
